UNITED STATES PATENT OFFICE.

ANDREW MOSEGARD, OF MORGAN HILL, CALIFORNIA.

FLOAT-CONTROLLED CIRCUIT-BREAKER.

1,187,645.

Specification of Letters Patent. Patented June 20, 1916.

Application filed April 26, 1915. Serial No. 24,036.

To all whom it may concern:

Be it known that I, ANDREW MOSEGARD, a citizen of the United States, residing at Morgan Hill, in the county of Santa Clara and State of California, have invented certain new and useful improvements in Float-Controlled Circuit-Breakers, of which the following is a specification.

This invention relates to improvements in 10 float controlled circuit breakers.

The invention has for its object to provide for automatically indicating the need of the replenishing of the water supply used in producing a cooling action upon the engine, as in maintaining the requisite height 15 thereof to guard against burning out of the engine.

A further object is to provide for stopping the running of the engine upon the water 20 reaching the low water-mark, accordingly guarding against the running of the engine in the absence of the cooling action of the water, the cause of the burning out of engines of this type.

25 A still further object is to carry out the aforesaid ends in a simple, inexpensive and effective manner and with facility.

The invention therefore consists of certain structural features including the combination and arrangement of parts substantially as hereinafter disclosed and defined by the appended claim.

In the accompanying drawings is illustrated the preferred embodiment of my invention, and wherein it will be understood that various changes and modifications as to the detailed construction and arrangement of parts may be made without departing from the spirit of the invention, and in 40 which drawing—

Figure 1 is a perspective view of my invention. Fig. 2 is a sectional elevation of the water-tank showing my invention in side elevation in connection therewith, the latter 45 also being shown in certain dotted line positions. Fig. 3 is a detailed side view of the magneto switch lever. Fig. 4 is a detailed perspective view showing more particularly the connection between the float-valve stem 50 and the water-tank containing the float valve.

In carrying out my invention, I provide, in connection with an ordinary water-containing tank 1 having a valved intake pipe 55 a and a valved water delivery pipe b , a float or valve 2 having its stem or rod 3

pivotedly connected, as at 4, to the inside of said tank, near the upper edge thereof, said float or valve being borne upon the water-surface and of course, controlled by the action thereof. Said float or valve stem 3 has loosely sleeved or carried thereon, a tubular member or sleeve 5, which sleeve is slideable upon said rod or stem, and has flexible or chain-connection 6 with a switch lever 7, for 60 controlling the ignition circuit of the engine, the ends of the chain or flexible connection being connected to the stem 7^a of said lever and the distant end of the tubular member or sleeve, respectively, as clearly seen in 70 Figs. 1 and 3. Said sleeve or tubular member 5, it will be seen, is of a relative length with respect to the float stem or rod 3 and so positioned initially thereon as that, when the latter is in horizontal position, and the 75 water-level accordingly at its maximum height, as indicated in Fig. 1, one end of said stem or rod will be distant from the pivotal connection between said stem or rod and the tank, whereby when the water level 80 lowers by the gradual evaporation of the water, the chain or flexible connection 6 will draw upon and gradually move the sleeve upon the float-stem or rod 3, which drawing action of the chain upon the sleeve will continue as the float-stem descends with the continued fall of the water from evaporation, the sleeve at a certain interval contacting with the point 4, as for instance, as indicated by the upper dotted line showing. At 85 this juncture, the sleeve will offer resistance to the chain or connection 6, as is apparent, and accordingly transmit the pull through the sleeve and effect the actuation of the switch-lever 7 connected in electric circuit 90 with the magneto with the further descent of the water until the float valve has reached its maximum descent or the low-water mark, as for instance, as indicated by the lower dotted line showing, the switch lever by that 95 time having been moved out of normal contact position, thus breaking the circuit established by the magneto 7^b wired as at 7^c with the battery 7^d and said switch-lever and its contact member 7^e accordingly providing for 100 the stopping of the engine.

Upon replenishing the water-supply to the tank 1, the float or valve will rise therein and provide for reestablishing the electric-circuit by the pulling of the lever 7^a 110 into engagement with its contact 7^e, thus putting the engine in operation, the water

being, in the first instance, supplied to the tank 1, and the water supply subsequently replenished via the pipe *a*, the water being delivered from the tank via the pipe *b* for cooling the engine, as well understood.

I claim:

A float controlled circuit breaker comprising a float, the position of which is determined by the level of the liquid in the supply tank or reservoir, said float being carried by a rod or stem pivoted to the supply tank, a switch, and means permitting lost motion

between the float and the switch, whereby the level of the float may fall a predetermined distance before the switch is opened, 15 said means comprising a sleeve slidably mounted on the rod or stem of the float and a flexible element between the outer end of said sleeve and switch.

In testimony whereof I affix my signature 20 in presence of a witness.

ANDREW MOSEGARD.
